UNITED STATES PATENT OFFICE.

ARTHUR A. ADAMS, OF BROOKLINE, MASSACHUSETTS, ASSIGNOR TO NATIONAL BINDING MACHINE COMPANY, OF BOSTON, MASSACHUSETTS, A CORPORATION OF MAINE.

STRIP-SERVING DEVICE.

1,166,106.

Specification of Letters Patent. Patented Dec. 28, 1915.

Application filed January 19, 1910. Serial No. 538,894.

To all whom it may concern:

Be it known that I, ARTHUR A. ADAMS, a citizen of the United States, residing at Brookline, in the county of Norfolk and State of Massachusetts, have invented an Improvement in Strip-Serving Devices, of which the following description, in connection with the accompanying drawings, is a specification, like letters on the drawings representing like parts.

This invention relates to strip serving devices.

In order that the principle thereof may readily be understood, I have disclosed a single embodiment thereof in the accompanying drawing, wherein—

Figure 1 is a side elevation partially in section of a strip serving device embodying my invention; Fig. 2 is a plan view thereof; Fig. 3 is a detail in vertical section of the moistener in non-operating position; and Fig. 4 is a detail in side elevation showing a slightly modified form of my invention.

One object of my invention is to provide a strip serving device that is compact and of comparatively few parts, and one wherein means are provided to position the strip in contact with an extended moistening area of the moistener and to prevent lateral deflection or uneven delivery of the strip during the serving operation.

Other objects of the invention will be more fully set forth hereinafter.

Referring specifically to the drawings, the base of the device is represented at 1, it being preferably a casting to upstanding portions 2 whereon is bolted or otherwise suitably secured a casing 3 adapted to receive a strip roll 4 which may be of the full width of said casing or of any less width. In operative relation to the strip roll support is a tank or reservoir 5 adapted to contain water for moistening the previously gummed strip, though within the scope of my invention some suitable adhesive may be contained therein and applied to an ungummed strip. The reservoir is of any suitable size and is positioned between lugs 6—6 upstanding from the base 1.

The moistener employed is preferably of a rotatable type as indicated at 7, it being represented as having a suitable fibrous cov-

ering 8. To support the moistener, I have herein provided upstanding sides 9 secured by screws 10 to the edge of the base 1 and 55 provided with bearing slots 11 for the reception of the pivotal pins 12 of the moistener.

I contemplate the provision of suitable means for maintaining the strip in contact with the moistener throughout an extended 60 area of the latter at all times; that is, during the strip serving operation and when the device is not in use. To this end, I employ a plurality of guiding members arranged in front of and in the rear of the moistening 65 area, which serve also to prevent lateral deflection of the strip and to maintain the same at all times in its true position or path with respect to the moistener so as to insure an even feed of the strip and a severance thereof at right angles to the strip edges.

In the present embodiment of the invention, and in order to simplify the construction, I provide strip guiding means which also serve as tie rods. These combined strip 75 guiding means and tie rods are represented at 13 and 14 and are preferably arranged respectively in the rear of and in advance of the moistening area, so as to confine the strip in contact with the moistener throughout an 80 extended area. Preferably also the strip guiding members and particularly the rear guiding member 13 are positioned in close proximity to the moistener, so as to direct the strip with exactness to the moistener and 85 to prevent lateral deflection. The strip guiding member 13 is mounted in the side walls 9, and beneath the same may if desired be provided a directing ledge or plate 15 for the strip.

Viewing Fig. 1, it will be apparent that the strip guiding member 14 is positioned in such proximity to the moistener or sufficiently overhangs the same to prevent removal or insertion of the moistener without 95 further separation of the strip guiding members 13 and 14. I provide an inclosure or confining means for the moistener having relatively movable parts or members which serve to retain the moistener in position and 100 in effect to lock the same therein, and at the same time to guide the strip, as previously described. To this end, I mount upon the sides 9 movable extensions 16, here shown

as levers pivoted at 17 upon said sides 9 and having partial bearings 18 adapted, when the parts are in operative position, to rest in alignment with the bearings 11 of said sides 9. Means may be employed to limit the swinging movement of said extensions or levers 16. For this purpose I have here shown the sides 9 as provided with slots 19 for the reception of pins 20 upon said extensions and also pins 21 upon said extensions to contact with the upper edge of said sides 9. In this manner, the movement of said extensions in each direction is limited.

15 The strip guiding member 14 is mounted in the upper portions of the extensions 16, and a suitable severing blade 22 is also preferably carried by said extensions. I have here shown the rear portion of the strip 20 severing blade as encircling and supported by the strip guiding member 14 for convenience of construction.

25 When it is desired to remove the moistener, the extensions 16 are depressed, as indicated in Fig. 3, thus opening or expanding the inclosure for the moistener. This action elevates the moistener into convenient position for removal. When the moistener is in operative position as indicated in 30 Fig. 1, the strip guiding member 14 overlies the moistener, so as in effect to lock or confine the same in position and the two strip guiding members 13 and 14 substantially inclose the moistener. It will be 35 noted that the severing blade 22 does not yield when the strip is deflected against the same for severance, as indicated in Fig. 1, as the pins 20 and 21 prevent backward movement of said extensions and blade.

40 The blade 22 is mounted tightly upon the strip guiding member 14 so as not to rock thereon.

I may provide means to displace or remove the end of the strip from its normal 45 path when the apparatus is not to be used for a substantial length of time, as for example every night, such means preferably serving to displace the end of the strip when the moistener is elevated by removal or 50 other purpose. In Fig. 4, I have represented effective means for accomplishing this result and consisting of crank arms 22^a preferably pivoted upon the strip guiding member 13 and having a loose connection 22^b with prolongations 22^c of the levers 16, so that when the said prolongations are 55 elevated, as indicated in Fig. 4, the crank arms 22^a are also elevated. Carried by or formed with the crank arms 22^a is a lifting member 22^d, herein also serving as a guide, and acting to elevate the free end of the strip into substantially the position shown 60 in said Fig. 4, and hence withdrawing it from its normal path to permit unobstructed 65 access to the reservoir and overlying parts.

I contemplate the provision of suitable means for preventing excess moisture from being presented to the strip. The moistener herein employed is preferably rotary and in conjunction therewith I have herein represented a scraper roll 23 mounted in inclined bearings 24, so that by its own weight it is wedged or forced into effective engagement or relation with the moistener.

The scraper roll does not present a sharp 75 edge to the moistener, and hence does not either remove an undue amount of moisture therefrom or in any way injure the structure of the moistener covering. The scraper itself may and preferably does rotate with 80 the moistener, and hence does not impart undue friction thereto, but makes a suitable line contact therewith.

I contemplate the provision of suitable means for tensioning the strip as it is delivered from the casing 3. Preferably I provide a tensioning means adapted peripherally to engage the strip roll and having external manipulating means. Herein for the purpose I have represented a weight 25 90 having a handle or manipulating portion 26 extending through a slot 27 in the casing, which slot acts as a bearing when it is desired to elevate the weight to relieve the tension, or for the weight to follow the 95 diminishing roll.

In conjunction with the described tensioning means I may employ a plate 28 serving to inclose the otherwise open face of the casing 3. I also provide a spindle 29 100 mounted in the wall of the casing and extending through the central opening in the strip roll and having a nut 30 of the usual type.

It will be apparent from the foregoing 105 description that the strip is maintained in effective engagement with the moistener throughout an extended area of the latter and that lateral deflection or unequal feeding or deliverance of the strip are prevented. The strip both during and after the serving 110 and severance is maintained in the same described engagement with the moistener, and the free end of the strip drops from the blade 22 and extends into space in convenient position to be grasped by the operative when a further supply thereof is 115 needed.

The device herein described is particularly intended for use in mills or factories 120 requiring almost constant use of the strip. In such cases, the device is so constantly used that the continual contact of any portion of the strip with the moistener throughout the described moistening area is of such comparatively brief duration as to prevent impairment of the strip or adhesive.

Having thus described one illustrative embodiment of my invention, I desire it to be understood that although specific terms are 130

employed, they are used in a generic and descriptive sense and not for purposes of limitation, the scope of the invention being set forth in the following claims.

5. Claims:

1. A strip serving device from which strips may be served for manual application, comprising in combination, a strip roll support, a strip moistener past which the strip may be served by draft by the operative, a plurality of transversely extending, relatively movable pressers in close proximity to the moistener to confine the strip in extended contact therewith and to prevent lateral deflection thereof, one at least of said pressers having a movable support, and a severing blade in proximity to the moistener and against which the strip may be drawn by the operative. 75
2. A strip serving device from which strips may be served for manual application comprising in combination, a strip roll support, a moistener roll past which the strip may be served by draft by the operative, a plurality of transversely extending, relatively movable pressers in the rear of and in advance of the moistening area of the moistening roll to confine the strip in contact with the moistener throughout said moistening area, one at least of said pressers having a movable support, and a severing blade in proximity to the moistener and out of the service path of the strip and against which the strip may be deflected from its service path by the operative for severance. 80
3. A strip serving device from which strips may be served for manual application comprising in combination, a strip roll support, a strip moistener past which the strip may be served by draft by the operative, strip guiding means to confine the strip in contact with the moistener and having a moistener-confining and also a moistener-releasing position, means to support said strip-guiding means in such positions, and a severing blade in proximity to the moistener. 85
4. A strip serving device comprising in combination, a strip roll support, a strip moistener past which the strip may be served by draft by the operative, relatively separable strip guiding means at opposite sides of said moistener, means for effecting such relative separation while maintaining said guiding means supported, and a severing blade operatively related to the moistener. 90
5. A strip serving device comprising in combination, a strip roll support, a strip moistener past which the strip may be served by draft by the operative, strip guiding means to lock the moistener in position, said strip guiding locking means being movable to moistener-releasing position without removal from its support, and a severing blade in operative relation to the moistener. 95
6. A strip serving device comprising in combination, a strip roll support, a readily removable strip moistener past which the strip may be served by draft by the operative, means to lock the moistener in position against removal, said means being movable into a supported position permitting removal of the moistener, and a severing blade operatively related to the moistener. 100
7. A strip serving device comprising in combination, a strip roll support, a readily removable strip moistener past which the strip may be served by draft by the operator, a strip guide constituting means to confine the moistener from removal, and a severing blade mounted upon said strip guide. 105
8. A strip serving device comprising in combination, a strip roll support, a strip moistener past which the strip may be served by draft by the operative, a casing for said moistener, and a plurality of tie rods serving also to confine the moistener, said tie rods being mounted for movement toward and from each other. 110
9. A strip serving device comprising in combination, a strip roll support, a strip moistener past which the strip may be served by draft by the operative, and an enclosure for said moistener having portions movable toward and from each other to permit removal of the moistener. 115
10. A strip serving device comprising in combination, a strip roll support, a strip moistener past which the strip may be served by draft by the operative, and an enclosure for said moistener having portions movable toward and from each other and to permit removal of the moistener and having a movable moistener support. 120
11. A strip serving device comprising in combination, a strip roll support, a strip severing blade, a strip moistener past which the strip may be served by draft by the operative, and means to support said moistener in depressed position for moistening or in elevated position for ready manual removal from said supporting means and from the strip serving device. 125
12. A strip serving device comprising in combination, a strip roll support, a strip moistener past which the strip may be served by draft by the operative, means to confine the strip during the operation of the device in contact with the moistener, a swinging support for said moistener, and a severing blade carried by said support. 130
13. A strip serving device comprising in combination, a strip roll support, a strip moistener past which the strip may be served by draft by the operative, strip guiding devices serving as an enclosure for said moistener and movable toward and from each other, and a severing blade in proximity to the moistener. 135
14. A strip serving device comprising in combination, a strip roll support, a strip

- moistener past which the strip may be served by draft by the operative, a strip guide to hold the strip in contact with the moistener during the operation of the device, and movable means to support the moistener and said guide.
15. A strip serving device comprising in combination, a strip roll support, a strip moistener past which the strip may be served by draft by the operative, and an inclosure for the moistener having portions movable toward each other to confine the moistener and movable from each other to release the moistener, and a strip severing device.
16. A strip serving device comprising in combination, a strip roll support, strip severing means, a strip moistener past which the strip may be served by draft by the operative, and means to support said moistener in one position for moistening and in another position for ready manual removal from the said strip supporting means and from the strip serving device.
17. A strip serving device comprising in combination, a strip roll support, a moistener, a scraper roll positioned by its weight in operative relation to said moistener, and means to move said moistener into operative position in proximity to said scraper roll and into inoperative position away therefrom.
18. A strip serving device comprising in combination, a strip roll support, a rotatable moistener, a scraper having an automatic wedging action with relation to said moistener, and means to swing said moistener into operative position in proximity to said scraper roll and into inoperative position away therefrom.
19. A strip serving device comprising in combination, a strip roll support, a strip moistener past which the strip may be served by draft by the operative, means to lock the moistener in position, said locking means having a moistener support, and a severing blade in operative relation to the moistener.
20. A strip serving device comprising in combination, a strip roll support, a strip moistener past which the strip may be served by draft by the operative, means to lock the moistener in position, said locking means having a moistener elevating device associated therewith, and a severing blade in proximity to the moistener.
21. A strip serving device comprising in combination, a strip roll support, a strip moistener past which the strip may be served by draft by the operative, means to lock the moistener in position and to guide the strip into contact with the moistener, said means having moistener supporting bearings associated therewith, and a severing blade in proximity to the moistener.
22. A strip serving device comprising in combination, a strip roll support, a strip moistener past which the strip may be served by draft by the operator, a strip guide constituting means to confine the moistener from removal, and means for imparting swinging movement to said strip guide, thereby to permit ready removal of the strip moistener.
23. A strip serving device comprising in combination, a strip roll support, a removable strip moistener past which the strip may be served by draft by the operative, a plurality of rods extending transversely of the strip in close proximity to the moistener to confine the strip in extended contact therewith and to prevent lateral deflection thereof, said rods being movable toward and from each other to prevent or to permit removal of the moistener, and a severing blade in proximity to the moistener and against which the strip may be drawn by the operative.
24. A strip serving device comprising in combination, a strip roll support, a moistener roll past which the strip may be served by draft by the operative, devices in the rear of and in advance of the moistening area of the moistener roll to confine the strip in contact with the moistener throughout said moistening area, said devices being movable toward and from each other to prevent or to permit removal of the moistener, and a severing blade in proximity to the moistener and out of the service path of the strip and against which the strip may be deflected from its service path by the operative for severance.
25. A strip serving device comprising in combination, a strip roll support, a strip moistener past which the strip may be served by draft by the operative, transverse strip guide members to confine the strip in contact with the moistener and to confine the moistener in position, said members being movable toward and from each other, and a severing blade in proximity to the moistener.
26. A strip serving device comprising in combination, a strip roll support, a strip moistener past which the strip may be served by draft of the operative, transverse tie rods constituting strip guiding means and pivotal supports for one of said tie rods to permit relative movement of the tie rods toward and from each other.
27. A strip serving device comprising in combination, a strip roll support, a strip moistener past which the strip may be served by draft by the operative, levers having bearings for the moistener and a strip guiding and moistener confining tie rod mounted in said levers.
28. A strip serving device comprising in combination, a strip roll support, a strip moistener past which the strip may be served

by draft by the operative, supports for the moistener movable into depressed or elevated positions and adapted to support the moistener stationarily in either position, and
5 moistener locking means carried by said supports.

In testimony whereof, I have signed my

name to this specification, in the presence of two subscribing witnesses.
